GUS ALMQUIST, OF PERRIS, CALIFORNIA.

TAMPING-BAR CLAMP.

Application filed January 27, 1926. Serial No. 84,191.

This invention relates to tamping devices employed for tamping down the concrete or cement used in the filling of pipe molds and the like, and has for its object the provision 5 of a novel clamp adapted to be mounted upon the tamping bar whereby to permit slippage as the material rises within the mold, the tamping element being moved upwardly automatically, the device being moreover so constructed and arranged that when 10 a mold is filled the tamping device may be released so that it will return to initial position ready for acting upon another mold.

An important object is the provision of a 15 device of this character provided with an easily operable handle for effecting the release, spring means being provided for holding the handle in a selected position.

An essential feature is the provision of a 20 take-up device to compensate for the inevitable wear on the shoes so that adjustment may be made for insuring proper operation regardless of whether the shoes be new and thick or old and thin.

An additional object is the provision of a 25 device of this character which will be simple and inexpensive in manufacture, easy to install, positive in action, efficient and durable in service and a general improvement in the art.

With the above and other objects and advantages in view the invention consists in the details of construction to be hereinafter more fully described and claimed and illustrated in the accompanying drawings, in 30 which:

Figure 1 is a side elevation of a tamping apparatus associated with a mold and showing my device applied,

Figure 2 is an enlarged elevation of the device itself,

Figure 3 is a longitudinal section showing the handle in locked position,

Figure 4 is a view similar to Figure 3 showing the handle in released position,

Figure 5 is a detail cross section on the line 5—5 of Figure 3,

Figure 6 is a view showing the adjusting means operated to permit continued use of old and thin shoes.

The remaining figures are detail views.

Referring more particularly to the drawings the letter A designates a conventional form of tamp operating mechanism for applying power to a tamp B for packing con-

crete or cement into a mold C such as a pipe mold or the like.

In carrying out the present invention I provide a peculiarly constructed clamp device which forms the operative connection 60 between the mechanism A and the tamp B for automatically permitting slippage as the material rises within the mold. This device comprises an elongated body designated broadly by the numeral 10 and including a 65 hollow portion or sleeve 11 through which the tamp B passes. This tamp is simply of bar formation with its lower end D widened to define a tamp head. The body 10 is formed at one side with a trunnion 12 for 70 connection with a connecting rod E operated by the mechanism A. At its sides the body is formed with spaced parallel ears 13 and between these ears the front wall is formed with an opening 14.

Located within the sleeve portion 11 is a bowed spring member 15 which has both ends 16 and 17 extended laterally over the lower and upper ends respectively of the body. The end 17 is quite long and somewhat curved to constitute attaching means for a leaf spring 18 which is reduced in thickness toward its free end and which is for a purpose to be described. Between this spring 15 and the tamping bar is a lining or shoe 19 extending beyond the ends of the body, and between the opposite side of the sleeve portion and the other side of the tamping bar is a similar lining or shoe 20. These shoes are of some material which will 90 exert considerable friction upon the tamping bar when forced into engagement therewith.

Located between the ears 13 is a cam head 21 having an elongated slot 22 therein 95 through which passes a pivot pin 23 engaged through the ears. This cam head is formed with an elongated bore 24 intersecting the slot 22 and having one end threaded for engagement therein of the threaded end of a 100 control handle 25 secured by a lock nut 26 or its equivalent. The cam head is further formed with a socket 27 intersecting the slot 22 and containing a coil spring 28 which bears against the pin 23 and against a closure 105 plug 29 screwed into the outer end of the socket. The purpose of this spring is to hold the parts in such position that the pin 23 will be at one end of the slot 22.

The cam head is provided for co-operation 110

with the spring 15, and has its heel portion formed with a slot 30 within which is journaled a roller 31 adapted to bear against the outer side of the spring 15 at its center for effecting compression thereof.

A very important feature is the provision of a block or plunger 32 which is slidably mounted within the bore 24 and which is engaged by the handle 25. The upper end of this block is cut away at an incline to define a wedging surface 33 bearing against the pin 23.

In the operation, it will be apparent that when the handle is swung downwardly to its locking position as shown in Figures 2 and 3, when the mechanism is operated to exert a tamping action on material in the mold, the tamping bar B may slide upwardly with respect to the body member 10, slippage occurring between the shoes 19 and 20 and the tamping bar. In this way it is evident that the material will be packed hard and tight, while at the same time the tamping member will be automatically moved upwardly when the material is thoroughly packed, no attention on the part of the operator being needed in carrying out this feature. When the mold has been entirely filled, and it is desired to start filling another, the operator grasps the handle 25 and swings it into the position shown in Figure 4 whereupon the roller 31 moves away from the spring 15 and releases the tension thereof upon the friction shoes and tamping bar so that the bar gravitationally descends to normal or initial position ready for a second cycle of operations.

When in the course of time the shoes 19 and 20 become worn and thin as indicated in Figure 6, it is merely necessary to loosen the nut 26 and turn the handle 25 in a clockwise direction so as to slide the plunger or block 32 upwardly along the bore 24. When this is done the wedging surface 33 engaging the pin 23, will move the cam head 21 laterally with respect to and toward the tamping bar so that the spring 15 may still exert a proper compressing action on the friction shoes. The purpose of the spring 28 is to take up any back-lash or lost motion which might interfere with the proper action.

From the foregoing description and a study of the drawings it will be apparent that I have thus provided a simply constructed, inexpensive and easily controlled and used clamping device for tamping bars which will efficiently perform all the functions for which it is intended and which on account of its adjustment feature may be used for a prolonged period without requiring replacement of the friction shoes. As the parts are few it is evident that there is little to get out of order so that the device should have the maximum durability.

While I have shown and described the preferred embodiment of my invention it is of

course to be understood that I reserve the right to make such changes in the form, construction and arrangement of parts as will not depart from the spirit of the invention or the scope of the subjoined claims. 70

Having thus described my invention, I claim:

1. In a device of the character described, a body member adapted for connection with a power tamping mechanism and formed with a sleeve portion, a tamping bar slideable through said sleeve portion, friction means within the sleeve portion for engagement with the tamping bar, means for applying tension to the means for permitting limited slippage of the tamping bar comprising a bowed spring located within the sleeve portion, a cam lever having a head pivoted with respect to the sleeve portion, the cam head carrying a roller at its heel portion engageable with the spring for compressing the same, and a leaf spring carried by the sleeve portion and engageable with the cam lever for maintaining the same in a selected position. 90

2. In a device of the character described, a body member adapted for connection with a power tamping device and formed with a sleeve portion, a tamping bar slideable through said sleeve portion, friction producing means within the sleeve portion engaging the tamping bar, means for applying tension to said means for permitting limited slippage of the tamping bar comprising a spring located within the sleeve portion, a cam lever having a head portion formed with an elongated slot, a pivot carried by the sleeve portion and passing through said slot, spring means within the head of the cam engaging the pivot, and means for shifting the cam head with respect to its pivot for varying the spring tension. 100 105

3. In a device of the character described, a body member adapted for connection with a power tamping device and formed with a sleeve portion, a tamping bar slideable through said sleeve portion, friction producing means within the sleeve portion engaging the tamping bar, means for applying tension to said means for permitting limited slippage of the tamping bar comprising a spring located within the sleeve portion, a cam lever having a head portion formed with an elongated slot, a pivot carried by the sleeve portion and passing through said slot, spring means within the head of the cam engaging the pivot, and means for shifting the cam head with respect to its pivot, for varying the spring tension, comprising a longitudinally screw operated 120 125 wedge member located within the cam lever and engageable with the pivot of the cam.

4. In a device of the character described, a body member adapted for connection with a power tamping mechanism and formed

with a sleeve portion, a tamping bar slide-
able within said sleeve portion, friction
shoes within the sleeve portion for engage-
ment with the tamping bar, means for ap-
plying tension to the shoes for permitting
limited slippage of the tamping bar, said
means comprising a spring located within
the sleeve portion, a pivoted cam member
engageable with said spring, and means for
adjusting the cam for varying the spring
tension.

5. In a device of the character described,
a body having a sleeve portion, friction shoes
within the sleeve portion, a tamping bar
15 slideable through the sleeve portion between
said shoes, a bowed spring member within
the sleeve portion, a cam head pivoted on
the body and having a heel engageable with
the spring for compressing the same and
20 the friction shoes, and wedge means for
shifting the pivot of the cam.

6. In a device of the character described,
a body having a sleeve portion, friction
shoes within the sleeve portion, a tamping
25 bar slideable through the sleeve portion be-
tween said shoes, a bowed spring member
within the sleeve portion, a cam head pivoted
on the body and having a heel engageable
with the spring for compressing the same
30 and the friction shoes, and means for shift-
ing said pivot point to vary the position
of the cam head with respect to the spring.

7. In a device of the character described,
a body having a sleeve portion, friction shoes
within the sleeve portion, a tamping bar 25
slideable through the sleeve portion between
said shoes, a bowed spring member within
the sleeve portion, a cam head pivoted on
the body and having a heel engageable with
the spring for compressing the same and 40
the friction shoes, means for shifting said
pivot point to vary the position of the cam
head with respect to the spring, comprising
a wedge element engaging the pivot and
located within the cam head, and means for 45
moving said wedge element.

8. In a device of the character described,
a body having a sleeve portion, friction
shoes within the sleeve portion, a tamping bar
50 slideable through the sleeve portion between
said shoes, a bowed spring member within
the sleeve portion, a cam head pivoted on
the body and having a heel engageable with
the spring for compressing the same and the
55 friction shoes, means for shifting said
pivot point to vary the position of the cam
head with respect to the spring, comprising
a wedge element engaging the pivot and
located within the cam head, means for mov-
ing said wedge element, 60 a handle screwed
into the cam head and engaging said wedge
member for controlling the position thereof.

In testimony whereof I affix my signature.
GUS ALMQUIST.
